UNITED STATES PATENT OFFICE

115,717

DESIGN FOR A PAIR OF SEMIRIM SPECTACLES

George P. Kimmel, Brookeville, Md.

Application July 8, 1938, Serial No. 78,350

Term of patent 14 years

To all whom it may concern:

Be it known that I, George P. Kimmel, a citizen of the United States, residing at Brookeville, in the county of Montgomery and State of Maryland, have invented a new, original, and ornamental Design for a Pair of Semirim Spectacles, of which the following is a specification, reference being had to the accompanying drawing, forming a part thereof.

In the drawing:

Figure 1 is a front elevation of a pair of spectacles, showing my new design;

Figure 2 is a rear view of the disclosure in Figure 1; and

Figure 3 is a plan view thereof, the temples being shown in a fragmentary condition for convenience of illustration.

The characteristic features of my design reside in a frame formed of a pair of oppositely disposed inner sidewise aligning spaced substantially semi-ovoidal shaped portions for seating on the top edges and against the upper portions of the

edges of the temple and nasal sides of the lenses, each of said portions including an arcuate top part, a depending curved temple side part merging at its upper end into the outer end of the top part, a depending curved nasal side part merging at its upper end into the inner end of the top part of greater length than the temple side part, oppositely curved with respect to the curvature of the temple side part and merging at its lower end in the upper end of an offset nose pad carrying portion, a nose bridging portion of compound curvature arranged between and merging at its ends into the inner ends of said top parts and attaching portions for the lenses extending from the said temple and nasal side parts at an inclination with respect to and disposed above the lower ends of such parts.

I claim:

The ornamental design for a pair of semirim spectacles, as shown and described.

GEORGE P. KIMMEL.
